CLAIM

The ornamental design for handle for doors of protection barriers for industrial machine, as shown and described.

DESCRIPTION

1.-3. Handle for doors of protection barriers for industrial machine

1.1 is a top view of a handle for doors of protection barriers for industrial machine;

1.2 is a perspective left side view thereof;

1.3 is a right side view thereof;

2.1 is a top view of a second embodiment of a handle for doors of protection barriers for industrial machine;

2.2 is a perspective left side view thereof;

2.3 is a right side view thereof;

3.1 is a top view of a third embodiment of a handle for doors of protection barriers for industrial machine;

3.2 is a perspective left side view thereof;

3.3 is a left side view thereof.
